UNITED STATES PATENT OFFICE.

JOHN S. STEVENSON, OF DETROIT, MICHIGAN.

CAR-DOOR-OPERATING MECHANISM.

No. 797,332.

Specification of Letters Patent.

Patented Aug. 15, 1905.

Application filed March 10, 1905. Serial No. 249,431.

To all whom it may concern:

Be it known that I, JOHN S. STEVENSON, a citizen of the United States, residing at Detroit, Michigan, have invented a certain new and useful Improvement in Car-Door-Operating Mechanisms, of which the following is a full, clear, and exact description, such as will enable others skilled in the art to which it appertains to make and use the same, reference being had to the accompanying drawings, forming part of this specification, in which—

Figure 1 is a cross-sectional view of a drop-bottom gondola car, showing my improved door-operating mechanism mounted thereon. Fig. 2 is a sectional view on line 2 2 of Fig. 1. Fig. 3 is a modified form of track-rail, and Fig. 4 is another modification of the track-rail.

This invention relates to a new and useful improvement in operating mechanism for car-doors, particularly that class wherein the doors form the bottom of the car when in their closed position, said doors being hinged to the center or side sills, as the case may be, to discharge the contents of the load outwardly or inwardly, as desired.

While I have shown my improved mechanism coöperating with outwardly-discharging doors, it is obvious that the same could be applied in combination with inwardly-opening doors, and also it will be obvious that instead of having the mechanism co-operating with longitudinally-arranged doors said mechanism could coöperate with transversely-arranged doors—such, for instance, as those found in the type of drop-bottom gondola cars shown in the drawings or hopper-bottom cars.

To this end my invention consists in the construction, arrangement, and combination of the several parts, all as will be hereinafter described and afterward pointed out in the claims.

In the drawings, 1 indicates the side walls of the car; 2, the side sills; 3, the center sills; 4, the doors hinged to the center sills, and 5, a hood or cover for the center sills. While these parts are shown as being made of wood, it is obvious that rolled or pressed steel members and sheets could be employed.

6 indicates a track in the form of an angle secured to the center sills and looking down under the door, said angle extending upwardly at the side of the car and being secured to the side sill. Instead of having this

angle continuous for each door it is obvious that pendants could be dropped from the side and center sills to which the track portions 7 could be secured. This track portion 7 is preferably inclined slightly and at a point under the free edge of the door is provided with a jog or bend 8, whose face is approximately at right angles to a link 9, whose roller 10 operates upon the track. This link 9 is pivotally connected to the free edge of the door, the lower end of said link preferably on the axle of the roller having connected to it a link 11, made up, preferably, of spaced pieces, as shown in Fig. 2. This link 11 is pivotally connected to a rock-arm 12, mounted on a rock-shaft 13, having the usual ratchet-wheel 14 at its end and the shank portion 15, the said ratchet-wheel coöperating with locking-pawls (not shown) in a well-known manner and the said shank being designed to receive a socket-wrench or operating-handle, (not shown,) as is well understood.

The operation of the device is apparent from Fig. 1. When the door is closed, the parts are in the position shown at the left in Fig. 1, in which it will be seen that the link 9 is located above the portion 8 of the track, so that the end thrust on said link or the load supported by the door is practically transmitted in lines parallel to the axis of said link. In this position of the parts the pivotal points of the rock-arm 12 and the link 11 are in straight lines commonly known as "positions of dead-center." To open the door, the rock-shaft 13 is rotated in the proper direction, so as to swing the rock-arm away from the free edge of the door, and in so doing the roller 10 will leave the track portion 8 and run along the track portion 7, permitting the free edge of the door to swing down, as shown at the right in Fig. 1.

In Fig. 3 I have shown a modified form of track and roller, the roller 10^a having a V-shaped groove in its periphery coöperating with an inverted-V-shaped track 7^a, whereby a guide is provided tending to prevent accidental lateral displacement of the roller. The track 7^a may be made of pressed steel whose integral end members, which are secured to the center and side sills, are so shaped at their points of attachment as to adapt themselves to the faces of the members to which they are attached.

In Fig. 4 I have shown another modification of the track in which instead of having the portion 7 of Fig. 1 straight the same is

curved, as at 7^b, which equalizes the power required to raise the door at all times during the closing operation. In this form it will also be seen that the jog or bend 8^b is at a greater angle to the adjacent track portion 7^b, so that the axial line of link 9 with respect to the plane of said bent portion 8^b is less than a right angle.

I am aware that minor changes in the construction, arrangement, and combination of the several parts of my device can be made and substituted for those herein shown and described without in the least departing from the nature and principle of my invention.

Having thus described my invention, what I claim as new, and desire to secure by Letters Patent, is—

1. In a door - operating mechanism for cars, the combination with a swinging door providing a part of the bottom of the car and having a link pivotally connected to its free end, of a door-supporting track below the car-body and having a transverse portion with which the opposite end of the link co-operates; substantially as described.

2. In a door - operating mechanism for cars, the combination with a pivoted door forming part of the bottom of the car, of a link pivotally connected to the free end of said door and extending below the car-body, a roller mounted in the outer end of said link, a transverse track below the bottom of the car and with which said roller co-operates, and means connected to the outer end of said link for operating the same and its connected door; substantially as described.

3. In a door - operating mechanism for cars, the combination with a pivoted door forming a part of the bottom of the car, of a link pivotally mounted on the free edge of said door, a door-supporting track suspended from the body of the car and below the bottom thereof for supporting the outer end of

said link, said track being so constructed that when the door is closed the load will be transmitted through the link upon the track in a direction approximately perpendicular to the portion of the track supporting the door, and means for operating the link; substantially as described.

4. In a door - operating mechanism for cars, the combination with the door, of a link pivotally connected to the free edge of the door, a roller mounted in the outer end of said link, a track comprising the portions 7 and 8 for coöperating with said roller, a rock-arm, a link for connecting said rock-arm and said door-link, and means for operating said rock-arm; substantially as described.

5. In a door - operating mechanism for cars, the combination with a swinging door forming a part of the bottom of the car and having a link pivotally connected to its free end, of a supporting-track with which the opposite end of said link coöperates, said track having a curved portion below the floor of the car over which the link operates so as to equalize the power required to close the door, and means for operating the link; substantially as described.

6. In a door - operating mechanism for cars, the combination with a swinging door having a link pivotally connected to its free end, of means for operating said link, and a supporting-track having a flat face at one end for supporting the link in the closed position of the door, the adjacent portion of the track being curved; substantially as described.

In testimony whereof I hereunto affix my signature, in the presence of two witnesses, this 2d day of March, 1905.

JOHN S. STEVENSON.
